(57) **CLAIM**

The ornamental design for a vehicle theme bed, as shown and described.

DESCRIPTION

FIG. 1 is a perspective view of a vehicle theme bed;

FIG. 2 is a back view of the vehicle theme bed of FIG. 1;

FIG. 3 is a front view of the vehicle theme bed of FIG. 1; and,
FIG. 4 is a side view of a vehicle theme bed of FIG. 1.

The side of the bed not shown forms no part of the claimed design.

The broken lines are for environmental purposes only and
form no part of the claimed design.
